FLETCHER D. HALLOCK AND LEWIS WARRINGTON CHUBB, OF PITTSBURGH, AND CHARLES T. GUILDFORD, OF EAST PITTSBURGH, PENNSYLVANIA, ASSIGNORS TO WESTINGHOUSE ELECTRIC AND MANUFACTURING COMPANY, A CORPORATION OF PENNSYLVANIA.

SPEED-CONTROLLING DEVICE.

Application filed January 18, 1919. Serial No. 271,460.

To all whom it may concern:

Be it known that we, FLETCHER D. HALLOCK, a citizen of the United States, and a resident of Pittsburgh, in the county of Allegheny and State of Pennsylvania, LEWIS WARRINGTON CHUBB, a citizen of the United States, and a resident of Pittsburgh, in the county of Allegheny and State of Pennsylvania, and CHARLES T. GUILDFORD, a citizen of the United States, and a resident of East Pittsburgh, in the county of Allegheny and State of Pennsylvania, have invented a new and useful Improvement in Speed-Controlling Devices, of which the following is a specification.

Our invention relates to speed-controlled mechanisms and it has special relation to electrically-operated spinning machines.

In ring spinning, the spindles, which carry the bobbins upon which the yarn is wound are each mounted in the center of a ring. These rings are mounted upon a ring rail which is moved upwardly and downwardly during the rotation of the spindles in order to impart to the yarn the helical form which it finally assumes upon the bobbin. As the yarn is fed from the front rolls to the bobbin, through the traveller which rotates about the ring, the tension on the yarn varies with the position of the ring rail and also with the diameter of the cop as it is formed upon the bobbin. If the spindles should be rotated at uniform speed throughout the spinning operation, therefore, the yarn would vary in character in accordance with variations in tension. It is requisite, therefore, that the yarn be maintained at approximately constant tension during the spinning operation.

An object of our invention is to provide a ring spinning frame in which the speed of rotation of the spindles will be varied in accordance with the position of the ring rail or in accordance with the diameter of the cop, or both, so as to compensate for the variable tension upon the yarn, caused by the position of the ring rail, the diameter of cop, or both.

A further object of our invention is to provide a spinning frame which shall be operated by a constant-speed motor.

According to the specific embodiment of

our invention herein illustrated and described, we mount upon the spinning-frame cylinder shaft, the cylinder of which causes the rotation of the spindles, a friction disk to which motion is transmitted by a second friction disk which is directly rotated by a constant-speed motor. The relative positions of the disks and, therefore, the speed of the cylinder shaft, is determined by the position of the ring rail, or by the diameter of the cop, or both.

Our invention may best be understood by reference to the accompanying drawings, in which Fig. 1 is an end elevation of a spinning frame equipped with our invention; Fig. 2 is a front elevation of the same, partly in section; Figs. 3 and 4 are front and side elevations, respectively, of a detail of a modification, and Figs. 5 and 6 are views of two different types of cops.

A constant-speed motor 1 is connected through friction disks 21 and 20, to a cylinder shaft 2, from the cylinder 2^a of which a plurality of spindles 3 are operated, in the usual manner, by means of suitable belts 4. Each spindle 3 is rotatably mounted upon a fixed rail 5 and projects upwardly through the opening 6 of a ring 6^a in a ring rail 7, around the flange of which ring 6^a is dragged, by the tension on the yarn, a traveller or small steel bow 8, through which the yarn is fed from the front rolls to the bobbin. The circular movement of the traveller 8 serves to initially twist the yarn.

The ring rail 7 is supported upon a plurality of rods 9 (only one being shown), which are pivotally connected to the outer ends of rocker arms 10. The rocker arms 10 are rigidly fastened to an operating shaft 11 to which is rigidly fastened a lever arm 18, the top of which is moved back and forth through an arc, with the shaft 11 as a center, for the purpose of imparting a rising and falling movement to the ring rail 7. A counter-weight 12 is secured to the shaft 11 in order to maintain a smooth and balanced operation of the ring rail 7.

The counter-weight 12 serves also to actuate the ring rail 7 upwardly. The downward movement of the ring rail 7, its length of travel and its limits of travel, relative to the top of the bobbin, are effected by the

well known builder mechanism, comprising a rotatable cam 13, a pivoted arm 15 actuated thereby, a hook or link 16 connected to the outer end of the arm 15, and a chain 17 connecting the hook 16 to the arm 18, through a swivel connection 19. The builder mechanism comprises also the usual worm, worm shaft, ratchet gear and pawl for controlling the successive ranges of movement of the ring rail 7, these parts being omitted from the drawing for simplicity's sake.

We mount the friction disk 20 upon the cylinder shaft 2, to be engaged by the rotatable friction disk 21 which is slidably mounted upon the rotor shaft 22 of the motor 1. The disk 21 is reciprocated along the shaft 22 by an arm 23, which is pivotally mounted at 24 upon the ring frame, and is adapted to be actuated about its pivot by a suitably designed cam 25, mounted upon the same shaft as, or otherwise mechanically connected to, the cam 13. The arm 23 is actuated in opposition to the actuation of the cam 25, and a roller 25^a, carried by the arm 23, is maintained in engagement with said cam, by a spring 26. The cams 13 and 25 are here shown as actuated by the motor 1, through a system of gearing 27, so that the same source of power which causes rotation of the spindles 3 serves to reciprocate the ring rail 7. Other forms of driving mechanism for the cams are within the scope of our invention.

The operation is as follows: The rotation of the motor 1 imparts to the cylinder 2, through the friction disks 20 and 21, a rotative movement which, in turn, is transmitted through the belts 4, to the spindles 3. The yarn, which is to be wound upon the spindles, is fed from the front rolls (not shown) through the travellers 8 which, if the ring rail 7 were stationary and if no yarn were fed from the front rolls, would be rotated on their supporting rings at the same speed as the spindles 3, and twist would thus be imparted to the yarn between the spindles and the front rolls. But, as the yarn is fed uniformly from the front rolls to the traveller, the peripheral speed of the traveller slips behind that caused by the spindle an amount equal to the length of the yarn fed out and this permits the twisted yarn to be wound on the bobbin. The reciprocation of the ring rail 7 imparts to the yarn, as it is fed from the front rolls, a motion of translation in addition to its rotative movement caused by the spindles 3, which is for the purpose of arranging the yarn in layers for convenience in unwinding in the next process.

The machine illustrated in Fig. 1 is designed for spinning conically-wound cops (usual for filler yarn) of the type illustrated in Fig. 5. Each layer of yarn is spun and

wound from empty bobbin at 28 to full bobbin at 29 in the form of a series of cones of yarn, one layer thick, each of the same altitude and each placed immediately above the preceding layer. The layers of yarn are necessarily placed at higher altitudes upon the spindle by the ring rail 7, which is actuated by the builder mechanism through a series of up-and-down movements of equal length, but differently positioned in height with respect to the spindles 3. With the cams illustrated at 13 and 25, the ring rail 7 will be actuated through three successive up and down movements or three cycles, each cycle being from 29 to 28 and back to 29, during one rotation of the cam shaft. Each cycle will cause the winding of two layers of yarn before the ratchet gear (not shown), of the builder mechanism will cause the ring rail 7 to begin another series of up-and-down movements upon a higher level.

This method of winding requires a decrease in spindle speed from 29, the then lower limit of travel of the ring rail 7, which represents spinning at full bobbin, to 28, the then upper limit of travel of the ring rail, which represents spinning at empty bobbin. This decrease in speed is not uniform but involves a small change in its rate of decrease, permissible because of the resultant change in tension on the yarn due to the upward movement of the ring rail 7 and the consequent shortening of the length of yarn between the ring rail and yarn guide. On the reverse movement, that is, from 28 to 29, an increase in speed is required with a small change in the rate of increase because of the change in tension of the yarn due to the downward movement of the ring rail and the consequent lengthening of the yarn between the ring rail and the yarn guide.

These speed changes are effected by a suitably designed cam 25 which will give the same number of complete cycles of speed changes during one revolution of the cam shaft as are produced by the ring rail cam 13, together with the proper rates of increase and decrease of speed during the cycle to compensate for the upward and downward movement of the ring rail.

The parts are thus so designed that, when the yarn is being wound on the smallest diameter of the cop, the disk 21 is in the full line position of Fig. 1, so that the speed of rotation of the spindles 3 is smaller than at any other time, and the ring rail is at the upper limit of its reciprocating movement.

In the case of warp bobbins, each layer is spun and wound on a given diameter of bobbin from successively lowered tops to successively heightened bottoms as shown in Fig. 6, beginning at empty bobbin 30, 31 and ending with full bobbin 32, 33.

This method of winding requires a differ-

ent average spindle speed for each layer, but changing within narrow limits as the ring rail ascends or descends, to compensate for the change of tension caused by the position 5 of the ring rail.

- These speed changes are effected by a specially designed cam which replaces the cam 25. This cam, shown in Figs. 3 and 4, comprises a series of cam surfaces ranging from 10 the minimum to the maximum diameter required to give the successive speed changes obtained between the extreme positions of the arm 23. Each of the series of cam surfaces is designed to give the necessary reciprocating movement of the arm 23 through a short distance to compensate for the yarn tension due to the position of the ring rail. This series of cam surfaces is in the form of helically arranged, semi-heart-shaped, 15 rectangular grooves 34 cut in a truncated cone 35, in which groove the guiding roller 25^a on the arm 23 moves. This cone of cam surfaces is free to slide along its shaft but is rotatably fixed thereto. The cam 13 of Fig. 25 1 is replaced by a heart-shaped cam 36.
- The operation is as follows: when the bobbins are empty, the cam roller 25^a is at 37, shown in Fig. 4, and the arm 23 is in the full-line position, shown in Fig. 1, which 30 gives nearly the minimum speed to the spindles 3. As the cam revolves, the roller 25 follows the grooves 34 and, during one revolution, gives a reciprocating movement to the arm 23 through a range wide enough 35 to compensate for the upward and downward movement of the ring rail 7. The roller then reaches the point 38 (automatically shifting the cam 35 along the shaft) which permits the arm 23 to shift one step 40 away from the full-line position and thus give to the spindles 3 a higher mean speed, which is permissible with the increased diameter of the cop produced by the added two 45 layers of yarn. The cam 34 gives the same reciprocating movement to the arm 23 to compensate for the varying tension on the yarn produced by the upward and downward movement of the ring rail. The roller 50 then passes automatically to the points 39, 40, etc., repeating the operations until the bobbin is completely filled, as shown in Fig. 6.
- The arm 23 oscillates within small limits, while assuming successive positions between 55 the extreme full-line and dotted-line, illustrated positions. These successive positions correspond to successive increases of speed of the spindle 3, in accordance with the diameter of the cop, and the small oscillations 60 compensate for differences in tension on the

yarn caused by the position of the ring rail 7.

By means of a suitably designed cam, it is thus possible to obtain a uniform tension, and hence, a uniform thickness of the yarn, 65 by providing for an increase in the rotation of the spindles 3 when the tension on the yarn is decreasing, and for a decrease when the tension is increasing. It will be obvious, however, that our invention is by no means 70 restricted to spinning machinery. We desire, therefore, that only such limitations shall be placed upon the claims as are directly imposed therein.

We claim as our invention:

1. In a spinning machine, the combination 75 with a reciprocable ring rail for carrying a ring surrounding a spindle, and a rotatable shaft for rotating said spindle, of a friction disk rotatable with said shaft, a constant-speed motor, a friction disk rotatable by said motor for engaging said first-named friction disk to cause rotation of said shaft, and means operatively connected to said motor for moving said second-named disk toward 80 and away from, the center of rotation of said first-named disk in accordance with the position of said ring rail.

2. In a spinning machine, the combination 85 with a reciprocable ring rail for carrying a ring surrounding a spindle, and a rotatable shaft for rotating said spindle, of a friction disk rotatable with said shaft, a constant-speed motor, a friction disk rotatable by said motor for engaging said first-named friction 90 disk to cause rotation of said shaft, a rotatable cam controlled by said motor for reciprocating said ring rail, and a cam mechanically connected to said first-named cam for actuating said second-named disk toward 95 and away from, the center of rotation of said first-named disk.

3. In a spinning machine, the combination 100 with a ring rail that is movable through a predetermined cycle and a rotatable spindle adjacent thereto, of means comprising a constant-speed motor for actuating said ring rail and said spindle and means comprising two friction disks and a cam mechanism operatively connected to said motor for controlling 105 the operative relation of said disks to vary the speed of said spindle in accordance with the position of said ring rail in its cycle.

In testimony whereof, we have hereunto 110 subscribed our names this 27th day of Dec., 1918.
